DESIGN FOR A PRINTING TYPE FONT

Imre Reiner, Lugano, Switzerland, assignor to The Bauer Type Foundry, Inc., New York, N. Y., a corporation of New York

Original application September 15, 1939, Serial
No. 87,243, now Design Patent No. 118,171, dated December 19, 1939. Divided and this application February 3, 1940, Serial No. 89,975

Term of patent 7 years

To all whom it may concern:

Be it known that I, Imre Reiner, a citizen of Hungary, residing at Lugano, Switzerland, have invented a new, original, and ornamental Design for Printing Type Font of which the following is a specification, reference being had to the accompanying drawing, forming part thereof:

The printing type font of the upper-case letters is a face view of the figures of the drawing showing my design.

The present application is a division of my application filed September 15, 1939, Serial No.
D-87,243 (now Design Patent 118,171 of December 19, 1939).

I claim:

The ornamental design for a printing type font,
as shown.

IMRE REINER.
